Primary Examiner — Katie Jane Stofko*(74) Attorney, Agent, or Firm* — Sand, Sebott & Wernow Co., LPA(57) **CLAIM**

The ornamental design for a pet chew toy, as shown and described.

DESCRIPTION

FIG. 1 is a perspective view of a pet chew toy in accordance with our design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof;

FIG. 7 is a left side elevation view thereof; and,

FIG. 8 is a section taken along line 8-8 of FIG. 6.

1 Claim, 5 Drawing Sheets# US D843,680 S
